UNITED STATES PATENT OFFICE

HERMAN R. FREUND, OF BROOKLYN, NEW YORK, ASSIGNOR TO INTERTYPE CORPORATION, OF NEW YORK, N. Y., A CORPORATION OF NEW YORK

CLEANING MACHINE FOR MAGAZINES AND MATRICES

Original application filed November 22, 1928, Serial No. 321,146, and in Germany May 24, 1929. Divided and this application filed November 30, 1929. Serial No. 410,791.

The present invention relates to improvements in apparatus for removing dirt or other foreign substances and tarnish and for otherwise cleaning matrices and the matrix-guiding channels in matrix magazines of the kind commonly used in line casting machines of the general class shown and described in Letters Patent No. 436,532 granted September 16, 1890 to O. Mergenthaler, the present application being a division of my prior application Serial No. 321,146, filed November 22, 1928, which has matured into Patent No. 1,804,381 granted May 5, 1931.

Experience has shown that the matrices and also the guiding channels therefor within the magazines of machines of this class accumulate dirt, grease and other foreign matter and also become tarnished or corroded incident to the use of such machines, and such accumulations of foreign matter and tarnish tend to clog or to offer undue frictional resistance to the descent of the matrices by gravity through the magazines which are usually inclined downwardly and forwardly to their matrix delivery end, and hence the matrices and also the guiding channels therefor within the magazine require cleaning periodically to remove such accumulations and tarnish in order to insure smooth or uninterrupted passage of the matrices through the magazine and to effect prompt and certain delivery of the matrices therefrom under control of the usual keyboard-actuated escape-
ments.

It has been a common practice, prior to the present invention, to clean the matrices by removing them from their magazines and placing them in a machine which subjected them to the action of a liquid cleaner or to the abrasive action of brushes, felt or rubber, and to clean the magazines by passing a specially designed brush up and down through the matrix guiding channels therein while the matrices are removed therefrom, but such cleaning methods have not been entirely satisfactory, because of the great amount of work required in removing the matrices from the magazine and replacing them therein, which was rendered necessary by such methods, the inability of such methods to thoroughly clean

the matrices and magazines, especially the matrix channels in the magazines which tend to accumulate dirt, grease, tarnish and other obstructing matter at the intervals in their length corresponding with the positions of the matrices when they are at rest therein, and because of other reasons.

The present invention provides a novel and improved apparatus whereby the matrices and the magazines may be cleaned thoroughly and simultaneously and while the matrices are contained in their magazines, thus avoiding the necessity of removing the matrices from their magazines and replacing them therein and thereby saving much time and labor.

In the accompanying drawing:—

Fig. 1 is a top plan view, partly broken away, of a magazine and matrix cleaning apparatus constructed in accordance with the present invention;

Fig. 2 represents a vertical section taken on the line 2—2 in Fig. 1 and looking in the direction of the arrows therein;

Fig. 3 represents a section on an enlarged scale, taken on the line 3—3 of Fig. 1 and looking in the direction of the arrows; and

Fig. 4 represents a section on an enlarged scale, taken on the line 4—4 of Fig. 1 and looking in the direction of the arrows.

Similar parts are designated by the same reference characters in the different figures of the drawing.

In this drawing, M represents a matrix magazine of the kind commonly used in machines of the class hereinbefore referred to, these magazines being usually composed of opposed plates *m* of metal, usually brass, which are spaced apart a distance equal to the width of the bodies of the brass or metal matrices *m*¹ and are formed on their inner sides with grooves in which the lugs *m*² on the four corners of the matrices slide or travel, the magazines being usually located in the machine so that they are inclined in a forward and downward direction so that the matrices will travel by gravity from the upper to the lower delivery end of the magazine, and the delivery of the matrices at the lower end of the magazine and from the respective

matrix-guiding channels therein is controlled by an escapement E one of which is provided for each matrix-guiding channel, as is well understood by those skilled in this art.

It will also be understood that in magazines of this class containing a full supply of matrices, the opposite or upper and lower ends of the magazine are open so that passageways are formed throughout the length 10 of the magazine in the spaces between or not occupied by the rows of matrices therein.

The cleaning apparatus provided by the present invention enables the entire magazine and the matrices contained therein to be rotated while immersed or submerged in a cleaning liquid, and after the magazine and its matrices have been thus submitted to a cleaning operation, they may be removed and washed and dried in any suitable manner.

20 The cleaning apparatus as shown comprises a tank 1 which is of a size to receive the usual standard magazine together with the matrices contained therein, this tank being supported at its opposite narrow sides by horizontal 25 trunnions 2 which rotate in bearings 3 in the upper ends of standards 4 the latter being mounted in stationary position upon a floor or other support. One of the trunnions has a sprocket wheel 5 fixed to its whereby it may 30 be rotated by a sprocket chain connected to an electric motor or other driving means, rotation of the sprocket wheel causing the tank 1 connected to it to rotate at a relatively slow speed in a vertical plane. One end of the tank 35 is preferably closed permanently and has a strip of wood or other relatively yieldable material 6 secured to it, the inner edge of this strip being formed with a rib 7 which is adapted to enter the lower end of the magazine in the space thereof between the top and bottom plates m, as is shown in Fig. 4, the innermost edge of this rib preferably projecting into the magazine sufficiently far to dislodge the lowermost matrices from their escape- 40 ments E, substantially as is shown in Fig. 4, so that the rib 7 will withstand the impact due to the dropping of the matrices toward that end of the magazine, when the latter is brought into lowered position, thereby relieving 45 the escapement E from the impact of the matrices. The strip 6 also abuts against this end of the magazine and thereby prevents endwise shift of the magazine toward the closed end of the tank 1, but it is slotted to 50 provide passages 8 through which cleaning liquid contained in the tank may flow into and out of the interior of the magazine. The opposite end of the tank is provided with a removable cover or head 9 which may be detachably connected to that end of the tank 1 which is open and provides for the insertion and removal of the magazine, clamping bolts 10 being shown in the present instance for securing the cover or head 9 in place and to form a 55 fluid-tight fit against the flange 11 which sur-

rounds the open end of the tank. The cover or head 9 is provided with a pair of angle irons 12 which are fixed to its inner side, and these angle irons are spaced apart a distance sufficient to receive and hold between them a strip of leather or other suitable yielding material 13 so that it abuts against the narrow side edges at the top of the magazine and projects into the upper open end of the magazine throughout the width thereof, so that this strip 13 will prevent endwise displacement of the magazine and will be in a position to be engaged by the matrices in the magazine and to arrest the dropping of the matrices toward the upper or wider end of the magazine when this end of the magazine is lowered by the rotation of the tank 1 about the center of the trunnions 2 as an axis, damage to the matrices being thereby avoided. The strip 13 is sufficiently thin to provide spaces at its sides 85 for the flow of the cleaning liquid into and out of this end of the magazine. Spacing strips or ribs 14 are preferably provided at the inner sides of the tank to engage the top and bottom plates of the magazine and thereby center it 90 in a direction transversely of the tank, and these strips will guide the lower end of the magazine into engagement with the lower rib 7 during insertion of the magazine into the tank.

In carrying out the cleaning operation with an apparatus such as that just described, the magazine to be cleaned containing the matrices which are also to be cleaned, is lowered into the tank 1 while the latter is at rest and its open end is uppermost and the cover or head 9 is removed, the magazine being lowered edgewise between the strips 14 until the lower end of the magazine is engaged on the ribbed edge 7 of the strip 6 which will extend across the full width of the lower end of the magazine and will project into it a distance sufficient to engage the lowermost matrices and to push them back slightly from their escapements, and assuming the tank 1 has been filled to a suitable extent with a suitable cleaning liquid which preferably has been pre-heated, the cover or head 9 is applied to the tank 1 to close it, the inturned flanges of the angle irons 12 being adjacent to the upper wider end of the magazine and the leather or similar strip 13 being thereby brought into a position within this end of the magazine where it will catch the matrices as they drop toward this end of the magazine during rotation of the latter, Fig. 3 showing the manner in which the angle irons 12 and the matrix arresting strip 13 are positioned at this end of the magazine. After the magazine containing the matrices has been thus introduced into the tank and the latter tightly closed, the tank containing the magazine is slowly revolved or rotated about the horizontal axis of the trunnions 2. Such rotation of the magazine and the matrices contained therein will cause

the cleaning fluid to flow longitudinally through the inside of the magazine, first in one direction and then in the opposite direction, as each end of the magazine is alternately brought into lowered position, and at the same time, the matrices will be caused to slide within the magazine, first toward one end thereof and then toward the opposite end thereof, incident to the slow rotation of the tank and the magazine therein. This shifting of the matrices alternately from the upper to the lower end of the magazine will cause a frictional rubbing of the matrices alternately against the matrix-guiding channels in the top and bottom plates of the magazine, due to the successive inversions of the magazine and its contained matrices, and this rubbing action will effectively dislodge or remove any dirt, grease, tarnish or corrosion or other foreign matter that may have accumulated either on the surfaces of the magazine which are engaged by the matrices or upon the matrices, and the flow of the cleaning liquid or solution substantially longitudinally within the magazine will produce a scouring action which will further clean and wash away any foreign matter present. The sliding movement of the matrices is particularly effective in removing dirt or grease from the matrix guiding channels in the magazine as the dirt or grease tends to accumulate in areas which are spaced apart in the length of the matrix-guiding channels at intervals corresponding to the length of the matrices, and the sliding motion of the matrices serves to effectively remove such accumulation of foreign matter. The cleaning solution used in the rotatable tank 1 may be a solution of chromic acid and water, soda and water, or a benzol or other hydrocarbon liquid or any other suitable cleaning liquid and the cleaning liquid may be used either hot or cold. Endwise movement of the matrices within the magazine during its rotation is insured, as the magazines are never completely filled with matrices from top to bottom, there being sufficient space in all of the matrix channels to permit the matrices therein to move lengthwise.

In the embodiment of the invention hereinbefore described, the magazine and the matrices belonging therein are cleaned as a unit, thereby avoiding the labor and delay occasioned by removing the matrices from the magazine, cleaning the matrices or the magazine, or both, separately and then returning the matrices to their proper channels in the magazine.

Further, in the embodiment described, thorough and rapid cleaning of the matrices and magazines is accomplished by the relative flow between the cleaning liquid and the magazine and matrices in a direction substantially longitudinally within the matrix-containing chamber of the magazine, aided by relative movement between the matrices

and the magazine produced by the movement imparted to the latter, such relative movement of the matrices producing a rubbing or abrading action between the matrices and the walls or surfaces of the magazine which they engage which will dislodge or wear away any accumulations of dirt, grease or other foreign matter that tend to collect at the points where the matrices normally rest in the magazine, the matter thus dislodged being washed away by the longitudinally flowing cleaning liquid.

It is preferable to employ the cleaning liquid while hot, as the cleaning liquid is then able to act more readily on the dirt, grease or other foreign matter, but the cleaning liquid may be used cold or without heating in carrying out the invention with a magazine rotating means such as that shown, since the range of longitudinal sliding movement of the matrices will produce a rubbing action which will be sufficient to insure the removal of the dirt or foreign matter, especially in the presence of the cleaning liquid.

I claim as my invention:—

1. Apparatus for interiorly cleaning the open-ended magazine of a line casting machine, comprising a closed, liquid-tight tank to contain the magazine and a treating fluid, supporting members for unobstructively engaging the open ends of the magazine to support it immovably in said tank with its open ends spaced from the walls of the tank opposite thereto and to provide communication between the interior of the magazine and the liquid containing portion of the tank, and means for rotating the tank and magazine about an axis transverse to the length of the magazine to cause flow of the treating fluid longitudinally therethrough.

2. Apparatus for interiorly cleaning the open-ended magazine and therein slidably contained matrices of a line casting machine, comprising a tank to contain a treating fluid, matrix confining members to extend over and engage the open ends of the magazine to support it and its contained matrices fixedly away from the walls of the tank and to engage and prevent the escape of matrices from the magazine, said members providing passages between them and the respective ends of the magazine for the flow of the treating fluid through the magazine, and means pivotally supporting the tank and the magazine for successive inversions about an axis transverse to the length of the magazine to cause the matrices in the magazine to slide alternately toward opposite ends of the magazine, while resting alternately on the top and bottom plates of the magazine.

3. Apparatus for cleaning the magazine and therein contained matrices of a line casting machine comprising a rotatably mounted tank to contain a treating liquid, means for supporting the magazine in said tank with

its interior in communication therewith to receive treating liquid therefrom and for rotation with said tank to cause travel of the treating liquid and the matrices in the magazine toward the ends thereof to clean the magazine and matrices, and matrix arresting members located in the tank to project into the respective ends of a magazine therein and to engage and arrest the travel of the matrices toward the respective ends of the magazine.

4. Apparatus for cleaning the magazine and therein contained matrices of a line casting machine comprising an elongated tank closed at one end and open at the opposite end to receive the magazine, positioning means between the sides of the tank to receive the magazine between them, a member at the closed end of the tank to project into the matrix delivery end of the magazine and thereby hold the matrices out of working engagement with their controlling escapements, a movable cover for closing the open end of the tank, a member carried by the cover and projecting, when the cover is applied, into the upper end of the magazine to engage and arrest the travel of the matrices toward said end of the magazine, and means supporting the tank for rotation about an axis transverse to the length of a magazine therein.

In testimony whereof I have hereunto set my hand.

HERMAN R. FREUND.
